FLOAT-VALVE MECHANISM.

1,156,719.

Specification of Letters Patent.

Patented Oct. 12, 1915.

Application filed August 29, 1914. Serial No. 859,218.

To all whom it may concern:

Be it known that I, ROBERT L. STOKES, a citizen of the United States, residing at Cincinnati, in the county of Hamilton and 5 State of Ohio, have invented new and useful Improvements in Float-Valve Mechanism, of which the following is a specification.

My invention relates to the flushing tanks of toilet rooms, and more particularly to 10 improvements in the means of opening and closing them.

The object of my invention is to afford a single float valve and a single float valve closer coöperating therewith of the kind 15 that closes gradually and at the same time noiselessly. I effect this object by means of the mechanism hereinafter described and also illustrated by the accompanying drawing in which like reference characters rep- 20 resent like parts in all figures.

Figure 1 is a vertical section of my invention showing the float and float stem in elevation. Fig. 2 is a detached view in elevation of the rod of Fig. 1. Fig. 3 is a de- 25 tached view in elevation of the flat rectangular-shaped end of the float valve lever of Fig. 1.

A is the bottom of the flushing tank.

B is the inlet pipe.

30 C is a separate downward extension of the inlet pipe.

D is the float valve water cup.

E is the anti-hammer stand pipe.

35 F is a flange-headed extension of the inlet pipe B.

G is a nut that binds the washers 3 and 5 and flange 6 to the bottom of the flushing tank.

7 is a double collar, one portion of which 40 is mounted on the inlet pipe B and the other portion of which is mounted on the extension C. 9 is a bore through that portion of said collar connecting the two collars proper, said bore forming a bearing for the 45 rod 10. 8 is a screw adapted to bind said collar to said inlet pipe.

11 is a foot attached to the lower end of 50 the rod 10. 12 is a recess in said foot adapted to receive the end of the rod 13, said foot 55 being adapted to support said rod 13, which in turn is adapted to carry and support the valve 15, comprising a recessed head or cup in which the valve seat 14 is seated and the

rubber bag 16 which is positioned within the anti-hammer E. 55

17 is a circular boss encompassing the mouth of the outlet opening 18 of said water cup D and adapted to engage the valve seat 14 and cut off the flow of water from the inlet pipe B into the extension C. 60

19 is a cap adapted to screw onto and securely close the upper end of the anti-hammer E.

20 is a guide through which passes the upper end 21 of the rod 13 and which is 65 adapted to admit a flow of water from the water cup D into the anti-hammer E at the moment of the closing of the valve 15.

22, 23, 24, 25, 26, 27, 28, 29 are threads adapted to effect the assembling of the vari- 70 ous parts described above.

30 is a valve actuating lever having the flat, rectangular-shaped end 31 and the perforations 32 and 33 which respectively are adapted to receive the hooked end 34 of the 75 rod 10 and the stud-pin 35, which stud-pin extends laterally and integrally from the outside face of the water cup D and is adapted to support pivotally said lever 30 mounted thereon. The flat, rectangular-shaped end 80 31 of said lever 30 is adapted to retard the movement of said lever upward in the water on the closing of the valve 15, and thereby lessen the force of the impact of the water at the time of the closing of said valve. 36 85 is a standard extending integrally and laterally from the outside face of said water cup, said standard having a perforation through the free end thereof. 37 is the arm of the float 38 and is attached to said stand- 90 ard by means of the pivotal screw 39. 40 is a screw extending transversely through said float stem and adapted to engage the valve actuating lever 30 during the downward movement of the float. 41 and 42 are hang- 95 ers adapted to vibrate on the pivotal screws 43 and 39 respectively, and are still further adapted to engage said valve actuating lever 30 at certain points thereof during down- 100 ward movement of the float. 44 is the bifur- cated end of the stem 37 and is adapted to receive the free end of said standard to which it is attached by means of the pivotal screw 39. 45 is a standard rising integrally upward from said float arm 37. 46 is a lock- 105 ing set-screw passing transversely through

said last named standard and is adapted to engage the upper end of said hanger 42 and prevent it from following the law of gravity at certain points of the travel of 5 said stem upward and downward.

Having thus described my invention in detail and by illustration, I will now describe it as a working mechanism.

The flush valve having been opened, the 10 water in the flushing tank has flowed out and the float 38 has descended to the point indicated in the drawing, and, by means of said screw 40 and said hangers 41 and 42, it has carried said valve actuating lever 30 down with it, thus opening the valve 15. The flush valve now being closed, the water begins to fill the tank and the float 38 begins to rise and for a short way upward the lever 30 remains in engagement with the 20 hanger 42 and the screw 40 as indicated in the drawing and the first stage or step of closing the valve 14 has begun. Were it not for the fact that the lever 30 is held down as aforesaid, the weight of the valve apparatus and the force of the inflowing water 25 would close the valve almost instantly and a jarring noise would be produced by the sudden impact of the water against the sides of the water pipes and the water cup D, and that too in spite of the anti-water hammer E. In so doing, the lever 30 would be brought rapidly upward, to prevent which or at least to arrest to a considerable extent this rapid movement upward of lever 30, the 30 flat, rectangular-shaped terminal 31 is attached to this lever, but that is not enough, and it is for this reason that the float arm 37 is attached directly over this valve actuating lever and the hangers and screw as 35 aforesaid attached to this arm. At a point still farther upward the screw 40 leaves the terminal 31 behind, but the hanger 42 remains in engagement with it. At a still farther point upward, the screw 46 engages the 40 upper end of the hanger 42, pushes it out of a direct perpendicular position and, following this movement, said valve actuating lever engages the shorter hanger 41. At a point still farther up, and at about the time 45 the float comes to a state of rest, said valve actuating lever again engages the hanger 41. Thus it is, right at the time when the float valve would have been very suddenly closed, by means of the aforesaid mechanism the 50 closing is made by a more gradual and steadier gradation. At the time of the closing of the float valve as aforesaid, a certain portion of the water in the water cup D is forced through the guide 20 and into the 55 anti-hammer E, where the sudden impact of this water is received by the elastic rubber bag 16, and it is in this way again that the danger of noise caused by the impact of the water as aforesaid is still further overcome. 60 Consequently, by the combined operation of 65

the several members of my aforesaid invention, I close a single float valve almost absolutely noiselessly.

Having thus described my invention in detail, by illustrations and as a working 70 mechanism, what I claim is:—

1. In a float valve mechanism, a valve stem having its upper end extending into an anti-water hammer device in combination with an inflated rubber bag positioned within 75 said anti-water hammer device and supported by said float valve stem.

2. In a float valve mechanism, an arm consisting of an arm proper, a screw passing transversely and downwardly therethrough, a standard extending integrally upward from said arm, a set-screw passing horizontally and transversely through said standard and in the same plane as that of said arm, a hanger pivoted on said arm and near 80 said standard, another hanger having an upward-extending arm pivoted on said first named arm near said last named hanger and at the pivoted end of said stem, said screw and said hangers being adapted to engage a 85 valve actuating lever and regulate its movement upward, said set-screw being adapted to engage the upper end of said hanger having an upward-extending arm and to force said hanger out of a perpendicular position. 90

3. In a valve mechanism a valve actuating closing lever having a flat, rectangular-shaped free end adapted to retard the upward movement of said lever through the 95 water of a flushing tank. 100

4. In a valve mechanism, a valve actuating lever having a flat, rectangular-shaped free end in combination with a float and a float arm, said arm consisting of an arm proper, a screw passing transversely and 105 downwardly therethrough, a standard extending integrally upward from said arm, a set-screw passing horizontally and transversely through said standard and in the same plane as that of said arm, a hanger pivoted on said arm and near 110 said standard, another hanger having an upward-extending arm pivoted on said first-named arm near said last named hanger and at the pivoted end of said last named arm, said screw and said hanger being adapted to engage 115 said valve actuating lever and regulate its movement upward, said set-screw being adapted to engage the upper end of said hanger having an upwardly extending arm and to force it out of a perpendicular position. 120

5. In a valve mechanism and in combination; a flushing tank; an inlet pipe having a 125 separate downward extension; a water cup adapted to unite the upper ends of said inlet pipe and said downward extension; an anti-water hammer device attached to said water cup; a rubber bag positioned within said anti-water hammer device; a valve stem 130

positioned within said downward extension of said inlet pipe and extending upward through said water cup and into said anti-water hammer device, said stem having 5 mounted thereon a cup-shaped valve with a separate seat therein, said valve being positioned within said water cup; a valve actuating lever having a flat, rectangular-shaped free end, the other end of said lever 10 being mounted on a stud extending laterally from the outside face of said water cup, said lever having a perforation through the extreme end of such mounted end portion; a rod adapted to engage said perforation by 15 means of a hooked upper end; a foot having a recess in its upper face attached to the lower end of said rod, said foot being adapted to support said valve stem which in turn is adapted to support the said rubber bag; 20 a float and an arm therefor, said arm having a perforation through its free end, a screw passing through said arm near said float, a standard rising upward therefrom and a hanger depending therefrom near said 25 screw, another hanger having an upward-extending arm depending therefrom near

30 said standard; a second standard extending integrally and laterally from the outside face of said water cup, said standard having a perforation through the free end thereof adapted to receive a screw, said screw being 35 adapted to receive the perforated, bifurcated end of said float arm; said screw and said hangers of said float arm being adapted to engage said valve actuating lever, said screw passing through said first standard of said float stem being adapted to engage said upward-extending arm and push said hanger out of a perpendicular position upon upward movement of the float; said rubber 40 bag being adapted to receive yieldably the impact of the water rushing into said anti-water hammer device at the time of the closing of said valve.

In testimony whereof I have hereunto set 45 my hand in presence of two subscribing witnesses.

ROBERT L. STOKES.
